FIG. 1

MAE LAKE

INVENTOR.

BY Martin E. Anderson

ATTORNEY.

UNITED STATES PATENT OFFICE

116,713

DESIGN FOR A PIN FOR SUPPORTING ORNAMENTAL MEDALS OR THE LIKE

Mae Lake, Denver, Colo.

Application March 27, 1939, Serial No. 83,847

Term of patent 3½ years

To all whom it may concern:

Be it known that I, Mae Lake, a citizen of the United States, residing in the city and county of Denver and State of Colorado, have invented a new, original, and ornamental Design for a Pin for Supporting Ornamental Medals or the like, of which the following is a specification, reference being had to the accompanying drawings, forming part thereof.

In the drawing:

I claim:

The ornamental design for a pin for supporting ornamental medals or the like, as shown.

MAE LAKE.
